UNITED STATES PATENT OFFICE.

HENRY D. CLARK, OF ROCHESTER, NEW YORK, ASSIGNOR TO HIMSELF AND BENJAMIN P. WARD, OF SAME PLACE.

COMBINED FARE-BOX AND LANTERN.

SPECIFICATION forming part of Letters Patent No. 335,340, dated February 2, 1886.

Application filed July 7, 1885. Serial No. 170,907. (No model.)

To all whom it may concern:

Be it known that I, HENRY D. CLARK, of Rochester, in the county of Monroe and State of New York, have invented certain new and useful Improvements in Combined Fare-Boxes and Lanterns, of which the following is a full, clear, and exact description.

Reference is to be had to the accompanying drawings, forming part of this specification, in which similar letters of reference indicate corresponding parts in all the figures.

Figure 1 is a sectional side elevation of one of my improved combined fare-boxes and lanterns. Fig. 2 is a sectional plan view of the same, taken through the broken line *xxxx*, Fig. 1. Fig. 3 is a sectional plan view of the same, taken through the line *yy*, Fig. 1. Fig. 4 is a side elevation of the lower part of the same.

The object of this invention is to provide combined fare-boxes and lanterns constructed in such a manner that a passenger can drop the fare into the fare-box, and that the passenger and conductor can both see the fare after it has been dropped in and before it has been discharged into the money-box, and can thus know that it is the correct amount.

The invention consists in the construction and combination of various parts of the combined fare-box and lantern, as will be herein-after fully described, and then pointed out in the claims.

A is the base of the lantern, which is made with close bottom and sides to allow it to serve as a money-box, and has a collar around its top to receive the bottom band, B, of the lantern-frame. Upon one side of the band B is a pin, B', and upon the other side is a staple, B'', to enter L-slots A' in the collar of the base A, and thus secure the said base to the said band. To the collar of the base A, at the opposite sides of the open upper ends of the slots A', are attached loops A'', to strengthen the upper edge of the said collar, weakened by the said slots. The staple B'', when the said staple and the pin B' are at the inner ends of the slots A', enters the slot in a spring-hasp, C, attached to the said collar, so that the base A and band B can be locked together by a

padlock, D, the arm of which is passed through 50 the staple B'', as shown in Fig. 4.

The guard-frame is made in two parts, one, E of which is rigidly attached to the band B, and the other, F, is separate, and is secured when closed to the stationary part of the frame 55 or to the band B by a spring-catch, G, or other suitable fastening. The upper end of the part E of the frame is rigidly attached to the top H, and the upper end of the part F is hinged to the said top, as shown in Fig. 1. To the 60 band B and the top H are secured metal strips I, to which are secured the edges of a wire-gauze partition J, which divides the interior of the lantern into two compartments.

At the lower and upper ends of the parts E 65 F of the frame are formed semicircular channels K, to receive the edges of the lower and upper ends of the globe L, which is made in two equal parts, the side edges of which meet at the central lines of the metal strips I, so 70 that the joints between the said edges will be covered by the said strips. To the part of the band B at the side of the partition J, next the hinged part F of the frame, is secured a semicircular bottom, M, in the middle part of 75 which is formed a socket, N, to receive the lamp O. The bottom M, as shown in Fig. 2, and the band B, as shown in Fig. 4, have numerous holes formed through them to allow air to have free access to the lamp to support 80 combustion. The lamp O is secured in place in the socket N by a spring-catch, P, attached to the partition J, and which engages with a pin, Q, attached to the said lamp O, as shown in Figs. 1 and 2, or by other suitable means. 85

R is a tilting plate placed upon the side of the partition J, next the stationary part E of the frame, and in line with the bottom M. The tilting plate R is attached to the rod S, which rocks in holes in the band B, and has 90 a button, T, attached to one end, so that the said plate R can be readily tilted to discharge the fares into the money-box A. The tilting plate R is held in a horizontal position by a spring, U, attached to it and to the lower edge 95 of the partition J, as shown in Fig. 1.

Beneath the part of the plate R that rises when the said plate is tilted is placed an in-

clined plate, V, to prevent the weight of the fares from turning the said plate R and escap-
ing from the money-box A, should the lantern
be inverted so as to allow the said fares to
5 rest upon the said plate.

In a slot in the side of the part of the globe
L, placed in the stationary part E of the
frame, is formed a slot in which is placed an
inclined chute, W, the outer end of which is
10 flared and rests upon a rod of the said part of
the frame, and through which the passengers
drop the fares.

The chute W can be made of glass and sepa-
rate from or solid with the part of the globe;
15 but I prefer to make it of metal or other mate-
rial not liable to break and detachable, so that
it can be taken out when it is desired to remove
the said part of the globe from the frame.

To the head H are pivoted the ends of a bail,
20 X, by means of which the lantern is carried.

In using the combined fare-box and lantern
the conductor receives an empty fare-box and
lantern at the office, and is provided with pack-
ages of money to make change for the passen-
25 gers, so that the passengers can drop the exact
fare into the chute W, which fare falls upon the
plate R, and remains there in full view of the
passenger and conductor until the conductor
tilts the said plate and discharges the fare
30 into the money-box A. At the end of the trip
the conductor delivers the combined fare-box
and lantern at the office and receives an empty
one for his next trip.

Having thus described my invention, I claim
35 as new and desire to secure by Letters Patent—

1. A combined fare-box and lantern, con-
structed substantially as herein shown and de-
scribed, and consisting of the base A, the frame

made in two parts, one, E, stationary and at-
tached at its lower end to a band, B, engaging 40
with the base A, and at its upper end to the
head H, and the other hinged at its upper end
to the said head, the globe L, made in two parts
and secured to the two parts of the frame, the
strips I, covering the joints of the globe and 45
provided with a wire-gauze partition, J, divid-
ing the interior of the lantern into two com-
partments, the perforated bottom M, provided
with the lamp-receiving socket N, and at-
tached to the band B at one side of the parti-
tion J, and the spring held tilting plate R,
50 pivoted to the said band B, and the inclined
chute W, passing through the part of the globe
attached to the stationary part of the frame, as
set forth.

2. In a combined fare-box and lantern, the
globe and its guard-frame made in two parts
and provided with a partition in the plane of
division, substantially as herein shown and
described, whereby one part can be opened 60
without giving access to the interior of the
other part, as set forth.

3. In a combined fare-box and lantern, the
globe and its guide-frame made in two parts
and provided with a partition in the plane of 65
division, in combination with the inclined
chute passing through the globe, and the
spring-actuated plate having an operating-rod
and arranged in the base-chamber of the lan-
tern, substantially as and for the purpose set 70
forth.

HENRY D. CLARK.
